UNITED STATES PATENT OFFICE

97,326

DESIGN FOR A BUTTER PRINT MACHINE

Charles Doering and Henry H. Doering,
Chicago, Ill.

Application February 15, 1935, Serial No. 55,454

Term of patent 14 years

To all whom it may concern:

Be it known that we, Charles Doering and Henry H. Doering, citizens of the United States and residents of Chicago, county of Cook, and State of Illinois, have invented a new, original, and ornamental Design for a Butter Print Machine, of which the following is a specification, reference being had to the accompanying drawing forming part thereof.

In the drawing:

The figure is a perspective view of a butter print machine showing our new design.

The non-disclosed side of the machine which

is opposite to the front side as shown on the drawing, is substantially the same in appearance and configuration as front side that is shown. The non-disclosed end of the machines which is opposite to the end shown, is plain in appearance. The dominant feature of our design resides in the configuration of the frame.

We claim:

The ornamental design for a butter print machine substantially as shown and described.

CHARLES DOERING.
HENRY H. DOERING.
